ALTERNATING CURRENT MAGNET

Rufus A. Andrews, Mount Vernon, N. Y., assignor
to Ward Leonard Electric Company, a corpora-
tion of New York

Application October 14, 1933, Serial No. 693,594

8 Claims. (Cl. 175—338)

This invention relates to alternating current magnets wherein a closed circuited path is provided for induced currents for the purpose of avoiding so called chattering or mechanical vibration of the movable part or parts.

The main objects of the improvement are to provide a form of construction and relationship of parts that will be of a simple character, require comparatively low manufacturing costs in material and labor, occupy small space, and accomplish its purpose effectively and efficiently. Other objects and advantages will be understood from the following description and accompanying drawing.

When an electromagnet is excited by an alternating current, the attractive force on the armature varies from zero to a maximum, and returns to zero, twice during each cycle. Consequently, under the influence of any external force, such as a spring or gravity, the armature will alternately leave and return to the core with a frequency corresponding to that of the alternating current, resulting in vibration and considerable noise, or humming. This may be largely overcome by some means for maintaining a flux continuously between the armature and core. It is common practice to use a shading coil or lag loop for this purpose. This loop embraces a portion of the core and has had the form of a single turn of copper, brass or similar material, inserted in the end of the core. This low resistance closed circuited conductor has appreciable self-inductance which causes a phase difference between the flux passing to the armature by way of that portion of the core embraced by the lag loop and the flux passing to the armature directly through that portion of the core not so embraced. Consequently, there is no period when there is not a flux between the armature and the core. This results in an attractive force always being exerted between the armature and the core and reduction of vibration and noise.

A conventional practice has been to use a laminated or solid magnet core with a straight slot completely traversing the core face, adjacent to the armature, and of such size that one leg of the lag loop may be placed in it. The core face is thus divided into two sections, the centers of which are displaced relatively to each other and to the axial center line of the core. The force of attraction due to the flux of each of these two sections is approximately concentrated at the mechanical center of each section. The respective lines of action of these two forces are mechanically spaced from each other by a distance

approximately equal to the center to center distance of the two sections. Unless the points of contact between the armature and the core are in a plane intersected by the line of action of both of the above forces of attraction, there will be resultant forces tending to rock or wobble the armature with a resultant noise of vibration. This rocking or wobbling effect may be reduced somewhat by careful machining of the core and armature. In some cases two straight slots are cut across the face of the core and two opposite sides of a rectangular shaped loop are placed in the two slots with the ends of the loop extending beyond the core. This gives a more symmetrical disposition of the flux but requires careful and costly machine work.

These prior forms of magnets are not efficient or fully satisfactory in accomplishing their purpose. They are also objectional, not only on account of the refined machine work required, but also because the straight slot or slots for the loop have to be milled in a separate milling operation after the core is otherwise finished. Furthermore, the portion of the lag loop which extends beyond the core face prevents the magnet coil from being uniformly wound thereover and thus prevents the attainment of a compact form of structure and reduces the efficiency. Again, in some forms of magnets, it is desirable to insert a centrally located spring or a movable part and this cannot be done when the lag loop passes across or near the central axis of the core. By the present invention these various objections and disadvantages are overcome.

The accompanying drawing illustrates a preferred embodiment of my invention in a particularly advantageous form of electromagnet for a particular purpose. Fig. 1 is a vertical central section of a controlling magnet and associated parts; Fig. 2 is a cross-section of the movable element of the magnet on the line A—A of Fig. 1; Fig. 3 is a view similar to Fig. 1 except that the ring loop is inserted in the face of the fixed core of the magnet, as distinguished from being inserted in the face of the movable element of the magnet; and Fig. 4 is a cross-section of the fixed core on the line B—B of Fig. 3.

Referring to Fig. 1, the parts are embraced and supported by a U-shaped steel member 1 and riveted thereto are two spaced transverse steel members 2. At the bottom of the inverted U-shaped member 1, is fastened a transverse plate 3 of insulating material which carries the binding posts and supports the fixed switch contacts 4. These switch contacts are diametrically oppo-

site each other. A dash pot 5, having a plunger 6, is supported in the upper part of the frame 1 and spaced from the top cross piece of the frame 1. A check valve 5a is located in the end of the 5 dash pot for permitting the plunger 6 to move down quickly when a downward force is exerted thereon. A stem or spindle 7 is secured at its upper end to the plunger 6. The spindle has an enlarged intermediate cylindrical portion 10 and 10 at its lower end carries a cone 8 of metal which is insulated from the spindle by the insulating intermediate portion 9. The cone 8 is adapted to engage the contacts 4 when the spindle is raised to its upper position, as shown in Fig. 1. A cylindrical steel core 11, having a central opening, is riveted, or otherwise secured, to the lower transverse plate 2, the lower end of the core 11 extending within a central opening in the plate 2. 15 A bridging cross plate 14 is riveted at its ends to the lower side of the lower cross plate 2 and has a central opening through which the spindle 7 passes. A spiral spring 12 encircles the spindle 7 and extends between the enlarged portion 10 of the spindle and the bridge plate 14. This spring, 20 by being supported at its lower end by the bridge plate tends to keep the spindle 7 and the dash pot 6 in their upper position and to keep the switch closed. The coil or winding M of the magnet is located between the two transverse plates 2 and 25 is wound upon a tube 13 of insulating material extending between the central openings of the plates 2.

The movable element of the magnet is in the form of a cylindrical steel plunger 15 having a 30 small central opening through which the spindle 7 passes and a larger central opening at its lower end for the reception of the enlarged portion 10 of the spindle. In the lower face of the plunger 15 a circular concentric slot is cut for the reception of the lag ring 16. This lag ring is shown in the form of a short cylinder and is tightly 35 forced into the slot so as to be firmly and permanently held therein. As shown in Fig. 2, a cylindrical concentric portion of the plunger 15 is embraced by the ring 16 and a cylindrical concentric portion of the plunger 15 envelops the outside of the ring 16. The ring is preferably made of copper but may be made of other conductive 40 material.

50 When in the position shown in Fig. 1, the cone 8 bridges the contacts 4 for the purpose of completing a circuit of some device which is to be controlled, the spring 12 holding the parts in their upper position. When the magnet winding M is energized, the core 15 is magnetically drawn 55 downwardly until it engages the fixed core 11, the plunger 6 of the dashpot and the bridging contact 8 being moved downwardly by the core 15 and causing the opening of the circuit to be controlled. As long as the winding M is excited, the parts will be held in their downward position. When the winding M is de-energized, the spring 12 will force the spindle and plunger 15 upwardly and cause the dashpot plunger to move against 60 the compression of the air in the dashpot. After a certain time element, the bridging switch element 8 will engage the contacts 4. Thus when the magnet M is excited, the controlled switch will be opened quickly and held open until the magnet M is de-energized, when after a certain 65 time interval, the switch controlled will again be closed.

In Figs. 3 and 4, the lag ring 16, instead of being inserted in the face of the movable ele-

ment 15, is embedded in the upper face of the fixed element 11.

It will be appreciated from the foregoing, that by use of a circular lag ring located concentric with the axis of the core, any rocking or wobbling effect is avoided because the lagging flux and the flux unaffected by the lag ring are concentric and are uniformly distributed around the center and maintain an attractive force having the same center. Also, owing to the fact that the lag ring 10 has no portions extending beyond the core, the magnet winding may be formed close to the core and thus be more efficient. Moreover, by placing the lag ring entirely within the contacting face of the core, the efficiency is increased because it 15 is entirely surrounded on the inside and outside by the iron or steel and the leakage flux is reduced to a minimum.

This improved form of construction also permits the center of the core to be hollow for the 20 reception of a spindle or counteracting spring, or other parts, without interfering with the location of the ring loop. In the particular application of this invention already described, it will be noted that an ample length of the spring 12 25 is provided so that within the range of movement of the plunger, the tension of the spring is not objectionably changed. It will also be noted that by reason of no projecting parts extending beyond the sides of the plunger or core, the air gap 30 between the same and the cross plates 2 may be made very small which, of course, increases the efficiency of the magnet. It will also be apparent that by making the lag ring concentric with the axis of the movable core, or with the axis of the 35 fixed core when placed therein, the machining of the cores may be accomplished in the least expensive manner, as the only machining necessary is to cut a circular slot in one end of the core at the time the core is being turned in a 40 lathe to its proper shape. Thus, by means of this invention, I am able to provide a magnet of a highly efficient type, compact in form, of low cost of manufacture and effective in avoiding the noise of vibration of the movable element.

45 Although I have shown my improvement applied to a solenoid form of magnet, the invention may be embodied in other forms of magnets and have the ring loop embedded in the face of either the fixed or movable element of the magnet; and it will be understood that various applications and adaptations of the invention may be made without departing from the scope thereof.

I claim:

1. The combination of a magnet winding, a 55 movable cylindrical magnetic element within said winding, said element having a central recess in one end thereof, a spiral spring having one end seated in said recess for moving said element in one direction, and a closed conducting circular ring in the face of said end of said element and concentric with the axis of said element

2. The combination of a magnet winding, a movable cylindrical magnetic element within said winding, a fixed cylindrical magnetic element 65 within said winding, one of said elements having a central opening, a spindle passing through said opening and engaging said movable element, and a closed conducting circular ring in the face of one of the adjoining ends of one of said elements and concentric with the axis thereof.

3. The combination of a magnet winding, a movable cylindrical magnetic element within said winding and having a central opening, a fixed cylindrical magnetic element within said winding 70

and also having a central opening, a spindle passing within said openings, a spring encircling said spindle for moving said movable element in one direction, and a closed conducting circular ring 5 in the face of one of the adjoining ends of one of said elements and concentric with the axis thereof.

4. An electromagnet having a cylindrical form of winding and having a fixed magnetic element 10 and a movable magnetic element, one of said elements being cylindrical and extending within said winding, a closed conducting circular ring in the face of the element extending within said winding, said ring being concentric with the axis of 15 the magnet and enveloped by said winding.

5. An electromagnet having a winding and a fixed magnetic element and a movable magnetic element, and a closed conducting circular ring inserted in the face of one of said elements, said 20 ring being continuously embraced on its outer side and on its inner side by portions of the element in which it is inserted.

6. An electromagnet having a winding and a fixed magnetic element and a movable magnetic

element, a closed conducting circular ring inserted in the face of one of said elements and concentric with the axis of the magnet, said ring being continuously embraced on its outer side and on its inner side by portions of the element 5 in which it is inserted.

7. An electromagnet having a winding and a fixed magnetic element and a movable magnetic element, one of said elements having a circular slot in its face concentric with the axis of said 10 winding, and a closed conducting circular ring inserted in said slot and being continuously embraced on its outer side and on its inner side by the walls of said slot.

8. An electromagnet having a winding and a 15 fixed magnetic element and a movable magnetic element, one of said elements having a circular slot in its face concentric with the axis of said winding, and a closed conducting circular ring inserted in said slot and being continuously embraced on its outer side and on its inner side by 20 the walls of said slot and being also enveloped by said winding.
